UNITED STATES PATENT OFFICE.

CAMILLE A. FAURE AND GEORGE TRENCH, OF FAVERSHAM, COUNTY OF KENT, ASSIGNEES TO THE COTTON POWDER COMPANY, (LIMITED,) OF WESTMINSTER, ENGLAND.

EXPLOSIVE BLASTING MATERIAL.

SPECIFICATION forming part of Letters Patent No. 244,575, dated July 19, 1881.

Application filed December 10, 1880. (No model.)

To all whom it may concern:

Be it known that we, CAMILLE ALPHONSE FAURE and GEORGE TRENCH, both of Faversham, in the county of Kent, England, have 5 invented a new and useful Improvement in Explosive Blasting Material, of which the following is a specification.

Our object is to provide an improved explosive material of the class which can be detonated and which is particularly adapted for blasting charges. The advantage of exploding by detonation over the mode of firing by a flame or spark is well established, especially when operating upon yielding material, such 10 as clay or gravel. Many explosive compounds of this class have been made by mixing with nitro-cellulose or such like substances an oxidizing agent and some carbonaceous substance—as charcoal or like combustible material—in such manner that the several ingredients became intimately intermixed each with each. It is found, however, that with those mixtures as heretofore commonly compounded it is necessary that they should contain a 15 rather large percentage of nitro-cellulose, in order to insure detonation under all the circumstances that present themselves in mining, and such compounds are therefore expensive.

30 We provide an explosive which can be detonated at a comparatively cheap rate.

In order to realize the maximum economy with the full power of the explosive, we do not mix or incorporate all the ingredients together, 35 as heretofore; but we first compound or incorporate the oxidizing agent—such as the nitrates of soda, potassa, or baryta—with the proper amount of carbonaceous material, (charcoal,) and with this mixture we form grains 40 that are hard and free from dust. To a given quantity of these so separately prepared grains—say ten parts by weight—we now add, say one part (more or less) of the nitro-cellulose previously purified and finely divided, and the 45 substances are uniformly distributed, so that each grain of the nitrated compound shall have

contiguous to it its proper proportion of nitro-cellulose.

This improved explosive material is put up or packed closely for use or transportation, so 50 as to prevent segregation of the substances or keep them in their uniformly-distributed condition. In this way the nitro-cellulose in the interstices between the grains, not being soiled or clogged by any other substance, remains 55 eminently apt to be detonated and to carry the detonation through the entire mass of granules, and by pulverizing and igniting them on the instant create the strongest possible effect.

60 The mode we use for firing the explosive is the same as that generally used with nitro compounds—*i. e.*, by means of a detonator with or without a priming-charge.

Although we prefer the above combination 65 of materials, we sometimes replace the grains of charcoal and niter by ordinary gunpowder; but the mixture described is safer to make.

It will of course be understood that the powdered or finely-divided nitro-cellulose is 70 added to the grains of gunpowder in manner as before explained.

In order to prevent the segregation of the materials during transit, we pack them rather tightly in barrels, cases, or charges; or we 75 cause the fibers of nitro cellulose to adhere to the grains by slightly covering these with an adhesive coat of varnish or such like substance. When the fine nitro-cellulose is mixed with the rough granules of gunpowder it does not readily separate from them. If the mixture is to be used at once, mere admixture is sufficient. If the mixture is to be transported from place to place, separation of the materials can be prevented by slightly pressing the mixture into packages; or if the mixture is to be carried in bulk, then it may be desirable, as 85 above stated, to use adhesive substance to cause the fine nitro-cellulose to adhere to the large grains.

90 The accompanying drawing represents a small mass of the above-described explosive

blasting material, *a* indicating the large grains and *c* the small grains (exaggerated in size) of nitro-cellulose distributed among them.

We claim as of our own invention—

5 The hereinbefore described improved explosive blasting material, consisting of intimately-mixed carbonaceous and oxidizing materials in granular form, with finely-divided nitro-cellulose distributed around the gran-

ules, substantially as and for the purpose described.

C. A. FAURE.
G. TRENCH.
